(57) **CLAIM**

I claim the ornamental design for a LED license plate light housing, as shown and described.

DESCRIPTION

FIG. 1 is a front isometric view of a LED license plate light housing showing my new design.

FIG. 2 is a rear isometric view thereof.

FIG. 3 is a front elevation view thereof.

FIG. 4 is a rear elevation view thereof.

FIG. 5 is a side elevation view thereof, with the opposite side being identical to that shown.

FIG. 6 is a top plan view thereof; and,

FIG. 7 is a bottom plan view thereof.

The broken lines are for environmental purposes only and form no part of the claimed design.

The claimed LED license plate light housing is characterized by the star-shaped cut on the top portion of the design.
